M. GUETT

ELECTRICAL FIXTURE

Filed Sept. 30, 1920

M. Guett
INVENTOR.

BY

Hans Schreiber
ATTORNEY.

UNITED STATES PATENT OFFICE.

MONROE GUETT, OF HARTFORD CONNECTICUT, ASSIGNOR TO THE HART & HEGERMAN MANUFACTURING COMPANY, OF HARTFORD, CONNECTICUT, A CORPORATION OF CONNECTICUT.

ELECTRICAL FIXTURE.

Application filed September 30, 1920. Serial No. 413,763.

To all whom it may concern:

Be it known that I, MONROE GUETT, a citizen of the United States, residing at Hartford, in the county of Hartford and State of Connecticut, have invented certain new and useful Improvements in Electrical Fixtures, of which the following is a specification.

This invention relates to what might be broadly considered an electrical fixture. While not restricted in this regard, the fixture generally takes the form of a plug and receptacle. This fixture can be associated with various parts, usually a ceiling or a wall and sometimes a floor, the invention not being restricted in any of these particulars and being as may be inferred rather fundamental in its scope. Various kinds of electrical appliances may be mechanically and electrically associated with the fixture. Among these might be mentioned electroliers in conjunction with which the fixture is of particular advantage. A fan or any other proper electrical appliance may be used with equal advantage.

At the present time there is in use an electrical fixture of plug and receptacle character. The receptacle of this old fixture contains the terminals to which the feed wires are electrically connected and usually in this old article the only mechanical connection between the two elements of the fixture is an electrical one. That is to say in the old structure the electrical means is utilized to mechanically connect the parts. One of the primary aims of my invention is to provide for the mechanical connection of the two elements of the fixture, by means separate and distinct or certainly mechanically independent of the electrical connection. There are a number of ways within the scope of the invention by which this important result can be obtained.

In the drawings accompanying and forming part of the present specification, I have shown in detail one of the several advantageous forms of the invention which to enable those skilled in the art to practice the invention will be set forth fully in the following description. Obviously I am not restricted to this showing. I may depart therefrom in many and radical respects within the scope of the invention defined by the claims following said description.

Referring to said drawings;

Figure 1 is a sectional side elevation of an 55 electrical fixture involving the invention, the section being on the line 1—1 of Fig. 2.

Fig. 2 is a bottom face view of the fixture.

Fig. 3 is a transverse section on the line 3—3 of Fig. 2. 60

Like characters refer to like parts throughout the several views.

As I have already noted the electrical fixture may take any one of several forms. In that relation which I have selected for illustration it is in the form of a plug and a receptacle, comprising a receptacle member as 2 and a plug member as 3. The receptacle member 2 might be considered as constituting the main or stationary member or element of the structure, while the plug member might be considered as the auxiliary or removable member of such a structure. It is conceivable that the two members of the fixture need not essentially be of receptacle 75 and plug type although such parts do possess their advantages.

The receptacle member 2 involves in its construction a face plate as 4 and which may as shown be in the form of a disk having a marginal upset flange as more or less common. This face plate also carries switch or equivalent mechanism enclosed in the box or housing 5, usually rigid with the face plate 4. As a matter of fact the construction thus far described is more or less old. 85

I have mentioned the fact that the members of the fixture are held in assembled relation by means independent of the electrical connection and I have alluded to the fact that these means might take various forms although studs, diametrically opposite each other have been found especially advantageous for the purpose, the studs being carried upon one of the members of the fixture and engaging catch means on the other. These studs and the co-operating catch means as will be understood, may take different forms, one of the many being shown. In this case the studs desirably diametrically opposite, are rigid on the plug as I will more particularly hereinafter explain, while the catch means is desirably upon the receptacle 2. The catch means which co-operates with the studs is also movable. 95 100 105

The plug 3 comprises an insulating body

6 against the under side of which the circular plate or disk 7 is fitted, the studs 8, of which there are two, diametrically opposite each other, extending through the disk 7 and being headed against the under surface of the disk to hold the plate or disk in position and to also maintain the studs in place. The heads 9 of the studs fit against the inner flat surface of the insulating body 6. Through the insulating body 6 the depthwise bore or passage 10, extends being in register with the bore or tube 11 which may and as shown be externally threaded to be mechanically connected with the fixture. The plug member 3 has fastened to it the prongs 12 held in place for instance by screws 13, these screws constituting a means for connecting wires mechanically and electrically to two prongs. When these prongs are electrically connected to the mechanism in the box or housing 5 the electric appliance mechanically connected with the tube 11, will be in electrical connection with such mechanism in the housing. The heads 9 of the diametrically opposite studs 8 as shown, have notches as 14 to receive operative portions of a locker. As will be understood this locker might be any one of several forms, the washer or plate 15 answering however satisfactorily in this connection. The lock washer or plate 15 is capable of rotary movement as I will herein-after describe, and it is held in position by the disk or plate 16 superimposed upon it and having a downturned peripheral or circumferential flange 17 abutting against the upper surface of the face plate 4 as shown best in Fig. 1. The disk or plate 16 also has the central flange or lip 16' constituting a pivot or journal for the locker or washer 15. The disk or plate 16 supports the box or housing 5 and the latter being mechanically connected with the face plate 4, it is clear that the box or housing holds the disk or plate 16 in position so that the latter can act as a casing or housing for the locker 15. As shown the face plate 4 has a central circular opening 18 and into this opening the central boss 19 of the box or housing 5 extends, the lower surface of the boss and the face plate 4 being flush or practically in the same plane with each other. The face plate 4 and the central boss 18 as shown have openings as 20 which when the locker 15 is in ineffective position, are adapted to receive the studs 8 at which time the studs can be thrust into said openings 20 until they bottom therein at which time the insulating body 6 will fit flatwise substantially against the face plate 4. The locker or washer 15 has on its inner side the notches or recesses 21 which when the locker is in its inoperative position register with these openings 20 so that the parts of the fixture may at this time be separably connected.

When they are connected at which time the studs 8 bottom in the openings 20, the locker will be moved to its effective position and when it is, the uncut portion of the inner side of the locker will be pushed into the notches 14. This motion of the locker can be brought about in any desirable way. For the purpose I have shown the stud 22 rotatively fitted in an opening in the face plate 4 and having means such as the slot 23 to receive a screw-driver or similar instrument by which it may be turned to impart working or opposite movements to said stud. As shown the locker 15 has in it the slot 24 to receive the crank 25 on the rotary stud 22. Through the rotation of this stud the locker 15 can be either advanced or retracted.

It will be assumed that the locker or circular washer 15 is in its ineffective position at which point the notches or recesses 21 on the inner side thereof are in register with the openings 20. This permits the insertion of the heads 9 of the studs 8 into the openings 20, the outer sides of the heads passing through the notches or recesses. When the parts are connected they will be locked in such relation by the turning of the locker 15 through the action for instance of a screw-driver, the edge of which is introduced into the slot 23 thus turning the stud 22 and causing the crank 25 to shoot the locker 15 and cause its solid inner side to be projected into the two notches 14 to hold the parts positively and substantially in solid relation. To free the plug member the stud 22 will be turned in the opposite direction thereby withdrawing the locker 15 from the notches 14 so that the plug member 3 can be pulled from the receptacle or socket member 2.

What I claim is:

1. An electrical fixture comprising a receptacle and a plug attachably associated therewith, and provided with means for securing an electrical connection therebetween when the members are connected and which is broken by the separation of the members, the plug having diametrically opposite notched rigid heads, the receptacle having a rotary internally notched ring which when the notches thereof register with said openings, permits the separation or connection of the plug and the receptacle, and cam means for turning the ring to cause the solid part thereof to enter the notches of the studs when the members are connected.

2. An electrical fixture comprising a receptacle and a plug attachably associated therewith and provided with means for securing an electrical connection therebetween when the members are connected and which is broken by the separation of the members, the plug having diametrically opposite notched heads and the receptacle having openings to receive said heads, the receptacle

also having a rotary internally notched ring which when the notches thereof register with said openings permits the separation or connection of the plug and the receptacle and a 5 manually operable cam on the receptacle to turn said ring to cause the solid part thereof to enter the notches of the studs when the re-

ceptacle and the plug members are connected.

In testimony whereof I affix my signature. 10
MONROE GUETT.
